UNITED STATES PATENT OFFICE.

THOMAS C. STARR, OF STOCKTON, CALIFORNIA.

ELECTRIC SIGN.

1,007,500.

Specification of Letters Patent. Patented Oct. 31, 1911.

Application filed May 2, 1910. Serial No. 558,869.

To all whom it may concern:

Be it known that I, THOMAS C. STARR, a citizen of the United States, residing at Stockton, in the county of San Joaquin,

5 State of California, have invented certain new and useful Improvements in Electric Signs; and I do declare the following to be a full, clear, and exact description of the same, such as will enable others skilled in 10 the art to which it appertains to make and use the same, reference being had to the accompanying drawings, and to the characters of reference marked thereon, which form a part of this application.

15 This invention relates to improvements in signs of all kinds and particularly to electric signs used for advertising purposes or the like the object of the invention being to produce such an electric sign as will give a 20 brighter and clearer display with the use of a minimum amount of light and also one which will be as effective as a day sign as an illuminated night sign.

A further object of the invention is to 25 produce a sign which employs a curved surface in order to illuminate both sides of the sign or background of a sign by the direct light from each and every lamp used.

I also aim to produce a simple and inexpensive sign and yet one which will be exceedingly effective for the purposes for 30 which it is designed.

These objects I accomplish by means of such structure and relative arrangement of 35 parts as will fully appear by a perusal of the following specification and claim.

In the drawings similar characters of reference indicate corresponding parts in the several views.

40 Figure 1 is a perspective view of one of the signs not inclosed. Fig. 2 is a similar view of an inclosed sign. Fig. 3 is a sectional view taken on a line $x-x$ of Fig. 1. Fig. 4 is a sectional view taken on a line $y-y$ 45 of Fig. 2.

Referring now more particularly to the characters of reference on the drawing, 1

designates the base of the sign which is substantially trough shaped and open at the top and which is the holder and reflector for 50 the lamps 2 which are arranged preferably in alternate order as shown in Figs. 3 and 4.

Disposed across the length of this member 1 is the sign proper comprised of a thin base portion 3 disposed substantially across 55 the center line of the lamps 2 thus receiving an equal portion of the direct light from said lights 2 which said portion 3 flares outward into curved portions 4 on each side which receive the full light from the lamps 2 60 thus making the sign stand out clearly and distinctly. The upper outer edges of the members 4 as at 5 are substantially aligned with the upper outer edges of the member 1 which causes the light to be evenly distributed and also permits side inclosures 7 to 65 be used, the sign then being displayed through suitable cut apertures 8. The members 4 may have a suitable inclosing top and supporting member 6 if desired. 70

I am aware that concave surfaces have been used before with lights used in front of them and I am also aware that both sides of a flat surface have been illuminated by the same lights by means of reflectors but 75 what I claim as my invention is the feature of the use of the curved surfaces in order to illuminate both sides of a sign or background by the direct light from each and every lamp used. 80

While this specification sets forth in detail the present and preferred construction of the device, still in practice such deviations from such detail may be resorted to as do not form a departure from the spirit of the 85 appended claim.

Having thus described my invention what I claim as new and useful and desire to secure by Letters Patent is:

A sign comprising a base member being of 90 a substantially V-shape such base being open at its top, lamps disposed on the sides of said base member in alternate order, said lamps projecting horizontally and being in

substantial horizontal alinement with each other, a narrow member disposed transversely across the central line of said lamps and having upwardly curving surfaces thereon, and side inclosing members projecting from the top edges of said curved surfaces to the top edges of said base member, said side inclosing members being perfo-

rated with letters or other designs as described.

In testimony whereof I affix my signature in presence of two witnesses.

THOMAS C. STARR.
